FILING CABINET FOR DRAWINGS, PLANS,
AND THE LIKE

Karl Möbus, Berlin, Germany

Application August 6, 1938, Serial No. 223,385
In Germany August 9, 1937

7 Claims. (Cl. 45-2)

This invention relates to cabinets in which drawings, plans or the like are filed or stored in a hanging or upright position the cabinet having tiltable front and top members, while on the inside of the back of the cabinet elements are provided on which the drawings or plans are suspended and into which stringing or threading pins attached to the inside of the front wall of the cabinet slide telescopically.

10 In a known cabinet of this type for filing drawings, plans or the like the drawings are suspended by means of rings attached thereto upon ridged, hollowed metal sleeves attached to the rear wall of the cabinet, while when the 15 cabinet is being closed curved pins attached to the front wall of the cabinet engage with the said sleeves, the latter being slotted on the underside. The hollowed sleeves are arranged upon brackets attached to the rear wall of the cabinet 20 in such manner that they are free to move slightly in a vertical plane, in order to compensate for any slight irregularity when the bent pins engage therewith.

According to the present invention both the 25 suspension elements on the rear wall of the cabinet from which the drawings are hung as well as the stringing pins attached to the front wall of the cabinet are mounted in such manner that they have considerable amplitude of vertical 30 movement which is limited by means of suitable stops arranged both above and particularly below said elements.

The suspension elements consist preferably of 35 tubes which are bevelled at their free ends and which, when the cabinet is closed, fit closely around the stringing pins.

The stops for limiting the movement of the 40 suspension elements and stringing pins consist preferably of adjustable abutment plates, arranged on the inside of the front wall and rear wall of the cabinet respectively and each provided with a slot through which the stringing and suspension elements pass.

The articulated attachment of the suspension 45 and stringing elements permits of considerable freedom of movement and this in turn makes it very easy to handle the cabinet when filing or removing drawings and the like. The aforesaid stops for limiting the degree of movement of the 50 suspension elements and stringing pins are preferably so adjusted that both the pins and the suspension elements tend to move downwardly when the cabinet is being opened, thereby facilitating the removal of the drawings and ensuring their careful handling. The bevel at the free ends

of the suspension elements also facilitates the transfer of drawings from the stringing pins to the suspension elements and the introduction of the stringing pins into said elements when closing the cabinet, thus also in this case ensuring 5 careful handling of the drawings.

An embodiment of the invention is illustrated by way of example in the drawing, in which:

Figure 1 is a plan view of the cabinet with the top removed and the front open.

Figure 2 is an elevational section on the line A—B in Figure 1, the top being shown in closed position.

Figure 3 is a section on line C—D in Figure 1 showing on an enlarged scale a detail of the 18 attachment of a stringing pin.

Figure 4 illustrates to a larger scale a fragment of a drawing or plan provided with a perforated suspending strip.

Similar reference numerals denote similar parts 20 in the several figures.

The cabinet consists in the usual manner of a base, a rear wall 3a, two side walls, a front wall 3 and a top 4 which is pivoted to the rear wall 3a by means of hinges 2. The front wall 3 25 is pivoted to the base by means of a hinge 4 so that it may be tilted out of the vertical or closed position into the open position shown in broken lines in Figure 2. The suspension elements on which the drawings, plans or the like 30 are hung are shown in the drawing as comprising tubes 6 pivotally attached to the outside of the rear wall 3a of the cabinet and passing through openings in the said rear wall and through abutment plates 16 attached on the inside of the said wall and provided with a slot. Straight stringing pins 5 attached in a similar 35 manner to the front wall 3 are adapted to telescope into these tubes 6.

According to the invention both the stringing 40 pins 5 as well as the suspension tubes 6 are articulated to the respective walls of the cabinet, so that both these pins and the tubes are permitted a certain amount of freedom of vertical movement, which is limited in both the upward and downward directions by means of suitable stops. For this purpose abutment plates 16 each formed with a slot, are attached to the rear wall 3a for the suspension tubes 6, while similar slotted abutment plates 15 are attached to the 45 front wall 3 of the cabinet for the stringing pins, said tubes and pins passing through the slots in the said plates. The plates 15, 16 are preferably attached to the respective walls of the cabinet 50 and positioned so that when the cabinet opens the 55

free ends of both the stringing pins and the suspension tubes tend to move downwardly, thereby considerably facilitating the removal of a drawing and contributing to careful handling of all the drawings, which on the front of the cabinet being opened automatically loosen and separate from one another owing to the inclined position of the suspension elements.

For the purpose of facilitating the stringing of the drawings or plans to be filed onto the suspension tubes, the latter are bevelled at their free ends, while the free ends of the stringing pins are rounded, so as to ensure easy introduction of said pins into the suspension tubes 6.

15 In order to enable the front wall 3 of the cabinet to be arrested in several different positions, for example, two, stop means are arranged on both sides of the cabinet. These stop means consist of two locating rails 9 articulated one at 20 either side of the tilttable front wall 3, each of said rails being at its free end provided with a bent lug 12 and, at a certain distance inwardly therefrom, with a notch 10. These locating rails cooperate with guide members 11 attached to the 25 inner faces of the side walls in such manner that the front can be arrested in two positions, one being that in which the notches 10 in the locating rails co-operate with the guide members 11, and the other being that in which the bent lugs 12 of 30 the locating rails 9 abut against the guide members 11 to hold the front wall 3 firmly. In the latter position of the front wall 3 the stringing pins 5 are out of engagement with the suspension tubes 6, so that a space is provided between the 35 free ends of said tubes and pins for the insertion or removal of the drawings.

Alternatively, other locating means such, for example, as simple chains may be used.

The drawings or plans 17 (Figure 4) to be filed 40 in the cabinet may be provided with a suitable reinforcement which prevents the perforations therein being torn, being preferably attached to a strip 18 provided with perforations, which strip is composed of somewhat stiff paper or similar 45 material. The suspension tubes and the stringing pins engage said perforations of the said suspending strip. The plans are preferably attached to the suspending strip by means of a strip provided with an adhesive. The suspending strips 18 50 prevent damage to the perforations in the drawings and need not be removed until the drawings are required for the preparation of prints by means, for example, of mechanical copying apparatus.

55 The suspending strips 18 may if desired be provided with any desired legend for the purpose of facilitating easy and orderly filing of the plans.

Upon the inner face of the top 1 there is preferably arranged a table of contents (not shown) 60 which gives a ready review of all the drawings and plans filed in the cabinet, so that any drawing and its serial number can at once be found.

What I claim and desire to secure by Letters Patent of the United States is:

65 1. Filing cabinet for drawings, plans and the like having a rear wall member and a tilttable front wall member, means on which said drawings are suspended in the cabinet comprising straight tubular suspension elements pivotally 70 attached for vertical swinging movement to the rear wall member, and straight stringing pins pivotally attached also for vertical swinging movement to the front wall member, said suspension elements and stringing pins telescoping to 75 form a rigid support for the drawings in the

closed position of the front wall member and disengaging from one another in the fully open position of said front wall member, and positioning means on said rear and front wall members limiting both the suspension elements and stringing pins to mutually registering positions in the disengaged position thereof, so that when the front wall member is swung toward the rear wall member said suspension elements and stringing pins will again telescope.

2. Filing cabinet for drawings, plans and the like having a rear wall member and a tilttable front wall member, means on which said drawings are suspended in the cabinet comprising straight tubular suspension elements pivotally attached 1 for vertical swinging movement to the rear wall member, and straight stringing pins pivotally attached also for vertical swinging movement to the front wall member, said suspension elements and stringing pins telescoping to form a rigid support for the drawings in the closed position of the front wall member and disengaging from one another in the fully open position of said front wall member, and hinge means connecting the lower portion of the front wall member to the 2 cabinet so that upon said front wall member being swung open on said hinge means the pivotal 3 mountings of the stringing pins on said front wall member will progressively swing downwardly so as to lower the outer ends of the suspension 4 element and stringing pin assemblages to inclined 5 positions in which said drawings will tend to slide 6 forwardly thereon toward the front wall member by the force of gravity.

3. Filing cabinet for drawings, plans and the like having a rear wall member and a tilttable front wall member, means on which said drawings are suspended in the cabinet comprising straight tubular suspension elements pivotally attached for vertical swinging movement to the 4 rear wall member, and straight stringing pins pivotally attached also for vertical swinging movement to the front wall member, said suspension elements and stringing pins telescoping to form a rigid support for the drawings in the closed position of the front wall member and disengaging from one another in the fully open position of said front wall member, positioning means on said rear and front wall members limiting both the suspension elements and stringing pins to mutually registering positions in the disengaged position thereof, so that when the front wall member is swung toward the rear wall member said suspension elements and stringing pins will again telescope, and hinge means connecting the lower portion of the front wall member to the cabinet so that upon said front wall member being swung open on said hinge means the pivotal 5 mountings of the stringing pins on said front wall member will progressively swing downwardly so as to lower the outer ends of the suspension 6 element and stringing pin assemblages to inclined 7 positions in which said drawings will tend to slide 8 forwardly thereon toward the front wall member by the force of gravity.

4. Filing cabinet for drawings, plans and the like having a rear wall member and a tilttable front wall member, means on which said drawings are suspended in the cabinet comprising straight tubular suspension elements pivotally attached for vertical swinging movement to the rear wall member, and straight stringing pins pivotally attached also for vertical swinging movement to the front wall member, said suspension elements and stringing pins telescoping

to form a rigid support for the drawings in the closed position of the front wall member and disengaging from one another in the fully open position of said front wall member, and slotted 5 means on said rear and front wall members through which the suspension elements and stringing pins project to limit the vertical movement of said suspension elements and stringing pins to mutually registering positions in the 10 disengaged position thereof, so that when the front wall member is swung toward the rear wall member said suspension elements and stringing pins will again telescope.

5. Filing cabinet for drawings, plans and the like having a rear wall member and a tilttable front wall member, means on which said drawings are suspended in the cabinet comprising straight tubular suspension elements pivotally attached for vertical swinging movement to the 15 rear wall member, and straight stringing pins pivotally attached also for vertical swinging movement to the front wall member, said suspension elements and stringing pins telescoping to form a rigid support for the drawings in the 20 closed position of the front wall member and disengaging from one another in the fully open position of said front wall member, positioning means on said rear and front wall members limiting both the suspension elements and stringing 25 pins to mutually registering positions in the disengaged position thereof, so that when the front wall member is swung toward the rear wall member said suspension elements and stringing pins will again telescope, guide members attached to 30 the side wall members of the cabinet and locating rails pivotally attached to said front wall member and cooperating with said guide members to arrest the front wall member at the fully open position and intermediate the fully open 35 position and the closed position of said front wall member in order to determine variously extended telescopied positions of the pins and tubular members and corresponding swung positions of the front wall member including a fully open 40 position thereof, in which the pins are spaced from the tubular members providing a gap between their adjacent ends for removal of individual drawings suspended on the suspension means, said locating rails being formed with lugs at their free ends and notches inwardly of said lugs adapted to engage said guide members.

6. Filing cabinet for drawings, plans and the like having a rear wall member and a tilttable front wall member, means on which said drawings are suspended in the cabinet comprising straight tubular suspension elements pivotally attached for vertical swinging movement to the rear wall member, and straight stringing pins pivotally attached also for vertical swinging 50 movement to the front wall member, said sus-

pension elements and stringing pins telescoping to form a rigid support for the drawings in the closed position of the front wall member and disengaging from one another in the fully open position of said front wall member, positioning 5 means on said rear and front wall members limiting both the suspension elements and stringing pins to mutually registering positions in the disengaged position thereof, so that when the front wall member is swung toward the rear 10 wall member said suspension elements and stringing pins will again telescope, hinge means connecting the lower portion of the front wall member to the cabinet so that upon said front wall member being swung open on said hinge 15 means the pivotal mountings of the stringing pins on said front wall member will progressively swing downwardly so as to lower the outer ends of the suspension element and stringing pin assemblies to inclined positions in which said drawings will tend to slide forwardly thereon toward the front wall member by the force of gravity, guide members attached to the side wall members of the cabinet and locating rails pivotally attached to said front wall member and 20 cooperating with said guide members to arrest the front wall member at the fully open position and intermediate the fully open position and the closed position of said front wall member in order to determine variously extended telescopied positions of the pins and tubular members and corresponding swung positions of the front wall member including a fully open position 25 thereof, in which the pins are spaced from the tubular members providing a gap between their adjacent ends for removal of individual drawings suspended on the suspension means, said locating rails being formed with lugs at their free ends and notches inwardly of said lugs adapted 30 to engage said guide members.

7. Filing cabinet for drawings, plans and the like having a rear wall member and a tilttable front wall member, means on which said drawings are suspended in the cabinet comprising mutually telescoping elongated members pivotally attached for vertical swinging movement to the front wall member and rear wall member, said elongated members forming a rigid support for the drawings in the telescoped condition thereof and disengaging from one another in the 45 fully opened position of said front wall member, and positioning means on said rear and front wall members limiting the downwardly vertical movement of said elongated members to mutually registering positions in the disengaged position 50 thereof so that when the front wall member is swung toward the rear wall member said suspension elements and pins will again telescope.

KARL MÖBUS.
